Primary Examiner — Catherine Tuttle(74) *Attorney, Agent, or Firm* — Womble Carlyle Sandridge & Rice, LLP(57) **CLAIM**

The ornamental design for a spray dispensing container, as shown and described.

DESCRIPTION

FIG. 1 is a top, front perspective view of a spray dispensing container showing my new design in a closed configuration; FIG. 2 is a side view thereof;

FIG. 3 is a side view thereof, wherein the container is rotated along a horizontal axis 180° in relation to the view illustrated in FIG. 2;

FIG. 4 is a rear view thereof;

FIG. 5 is a front view thereof;

FIG. 6 is a top plan view thereof;

FIG. 7 is a bottom plan view thereof;

FIG. 8 is a top, front perspective view showing my design in an open configuration; and,

FIG. 9 is a bottom, rear perspective view of the closed spray dispensing container shown in FIGS. 1-7.
